CONVERSION OF HYDROCARBONS

Frederick E. Frey, Bartlesville, Okla., assignor to
Phillips Petroleum Company, a corporation of
Delaware

Application March 11, 1940, Serial No. 323,443

11 Claims. (Cl. 196—10)

This invention relates to the catalytic production of higher boiling hydrocarbons from lower boiling hydrocarbons and more particularly to the catalytic union of paraffin and unsaturated hydrocarbons in the presence of hydrofluoric acid. This application is a continuation in part of my copending application, Serial No. 315,063, filed January 22, 1940.

Many processes have been proposed for converting low boiling hydrocarbons into higher boiling hydrocarbons, such as the production of motor fuels and lubricants from less viscous, more volatile, or normally gaseous hydrocarbons. Some of these processes are dependent upon having olefin hydrocarbons, or other unsaturated hydrocarbons, present in large proportions in the charge stock, such as in well known thermal and catalytic polymerization processes for producing motor fuel from refinery gases containing light unsaturated hydrocarbons from cracking stills. Still other processes have been proposed to produce heavier hydrocarbons from lighter paraffin hydrocarbons, such as thermal conversion under pressure whereby scission of the paraffins and polymerization proceed concurrently to produce conversion, or multistage processes employing a dehydrogenation step as a first part of the process, followed by one or another variety of conversion polymerization involving the olefins so produced.

This invention relates particularly to the alkylation of paraffin hydrocarbons to produce alkyl derivatives thereof, or in other words, higher boiling paraffin hydrocarbons, in the presence of a new catalyst for this reaction, and it also relates to certain preferable methods and process arrangements for alkylating paraffins in the presence of this catalyst to obtain high yields of preferred paraffin hydrocarbons, or specific paraffinic hydrocarbon fractions of predetermined boiling ranges and characteristics. I have found that concentrated hydrofluoric acid, under conditions to be set forth, will act as a catalyst to effect a union of unsaturated hydrocarbons with paraffin hydrocarbons to form higher boiling paraffin hydrocarbons. I have further found that it is preferable to use as a catalyst for this reaction substantially anhydrous hydrofluoric acid, or hydrogen fluoride, and that it can be effectively and safely used over a wide range of temperatures. I have also found that, although metal halide catalysts such as boron trifluoride have been used in the presence of appreciable quantities of finely divided metallic nickel and hydrogen fluoride to catalyze the reaction of paraffins and

olefins to form higher boiling paraffins, the presence of such other materials as finely divided metals and/or metal halides is not necessary for my invention, and that I can use concentrated hydrofluoric acid as a catalyst for the alkylation of paraffin hydrocarbons in the absence of finely divided nickel, metal halides, and the like. Thus, when reference is made hereinafter, in the specification or in the claims, to concentrated hydrofluoric acid or to substantially anhydrous hydrofluoric acid, it is to be understood that I regard the hydrofluoric acid as being the sole catalytic material. Although the metal walls of the reaction chambers or vessels may at times have some fortuitous promoting effect, the process has been carried out in the presence of numerous metals without appreciable differences being noted, so that such effects of gross masses of metal are substantially negligible if at all present. 10 The present invention relates particularly to the alkylation of normal paraffins, such as normal butane and/or normal pentane, with olefins in the presence of concentrated hydrofluoric acid. In one modification it relates to a process 15 wherein isoparaffins are more or less completely and selectively alkylated in the presence of normal paraffins, heavier hydrocarbons so produced are removed, and unreacted paraffin hydrocarbons are alkylated in the presence of concentrated hydrofluoric acid under conditions adapted 20 to react substantial portions of normal paraffins. Thus, I have found that normal paraffins can be alkylated by reaction with olefins in the presence of concentrated hydrofluoric acid at temperatures 25 above about 100 or 120° F. to form paraffinic products of higher molecular weight than the original normal paraffins. I have also found that at temperatures no higher than about 100° F., and often appreciably lower than this, a mixture 30 of isoparaffins and normal paraffins can be subjected to alkylation with olefins in the presence of a suitable alkylating agent and the alkylation so controlled that substantially only isoparaffins undergo reaction, leaving normal paraffins substantially or completely unreacted, in a more 35 concentrated state, and suitable for subsequent alkylation with olefins in the presence of concentrated hydrofluoric acid at more elevated 40 temperatures. Catalysts which may be used for the alkylation of isoparaffins include aluminum chloride and bromide, boron chloride and fluoride, concentrated sulfuric and sulfonic acids, and 45 concentrated hydrofluoric acid. The latter is the most preferable catalyst for use in this first step, as the first step and the second step can be more 50 55

closely cooperatively combined, as will be further discussed hereinafter.

It is an object of this invention to produce higher boiling paraffin hydrocarbons by the alkylation of lower boiling paraffins.

Another object of this invention is to use hydrofluoric acid as a catalyst in alkylation reactions involving only aliphatic hydrocarbons.

Still another object of my invention is the conversion of low boiling normal paraffins to higher boiling paraffins by alkylation with unsaturated hydrocarbons.

A further object of this invention is to establish a process wherein synthetic conversion stocks composed of hydrocarbons of simple and controlled composition can be converted in the presence of concentrated hydrofluoric acid to produce paraffinic liquid fractions having especially desirable characteristics and controlled properties, reflecting closely the identities of the reactant hydrocarbons selected.

An object of my invention is a process for the alkylation of paraffins with olefins in the presence of substantially anhydrous hydrofluoric acid to produce various simple branched paraffins or a mixture of simple composition within a wide range of boiling points or volatilities.

Another object is to effect the efficient recovery by physical means of hydrofluoric acid when used as a catalyst in the alkylation of paraffins with olefins.

Another object is to alkylate isoparaffins selectively with olefins when in a mixture comprising isoparaffins and normal paraffins to form higher boiling paraffin hydrocarbons, and subsequently to alkylate normal paraffins from said mixture with olefins in the presence of concentrated hydrofluoric acid.

Further objects and advantages of my invention and process will be found in the accompanying disclosure and discussion.

Catalysts which effect the alkylation of paraffins with olefins include active metal halides such as aluminum chloride, especially in the presence of small amounts of the corresponding hydrogen halide, certain complex salts such as sodium chloroaluminate, and concentrated sulfuric acid, a strong oxygen-containing, polybasic acid. However, these and similar catalysts have one or more disadvantages, chief among which are the promotion of unwanted side reactions, and more or less rapid deactivation of the catalysts accompanied by chemical reactions involving these materials. Thus aluminum chloride, boron trifluoride, and similar metal halides form addition compounds with olefin hydrocarbons which sooner or later degenerate into black, tar like masses which not only represent a deactivation of catalytic materials, but also represent a loss of valuable hydrocarbon material and necessitate involved procedures for eliminating such materials and recovering the metal halide in a form suitable for subsequent use. Sulfuric acid, which has recently found wide commercial application as an alkylating catalyst, has somewhat similar disadvantages. While apparently it does not form such definite intermediate compounds with olefin hydrocarbons as do various metal halides, there apparently is associated with its use a formation of various organic compounds, which after a time render the acid much less active, so that sulfuric acid which contains only 10 or 15 percent of such organic material must be replaced with fresh, uncontaminated acid. Sulfuric acid is also a powerful oxidizing agent, so that it cannot be

used at temperatures much above about 100 to 125° F. without too extensive deleterious side reactions that consume both sulfuric acid and valuable organic material. The spent acid can be partly reclaimed by more or less elaborate chemical means such as hydrolysis with water, removal of the oils thereby released, and reconcentrating by distilling out the water.

Concentrated hydrofluoric acid, when used as an alkylating agent for the alkylation of paraffin hydrocarbons, apparently does not possess these deleterious characteristics. It is essentially a non-oxidizing and no-reducing material, so that it can be used, and treated, at elevated temperatures without the undesirable side reactions just mentioned. While somewhat more dilute concentrations may be used, I prefer to use it in concentrations greater than 80 percent by weight, the other material being water, and I have found that substantially 100 percent hydrofluoric acid, that is, substantially or completely anhydrous hydrofluoric acid or hydrogen fluoride, is very effective, and is particularly adapted to the process arrangements to be hereinafter described more fully. As will be discussed, the process is generally carried out with the hydrocarbon material substantially in liquid phase; efficient reaction results when sufficient hydrofluoric acid is employed to result in a substantial saturation of the liquid hydrocarbon material with hydrogen fluoride, and preferably sufficient hydrogen fluoride is used to form a separate liquid phase which may be maintained emulsified or intimately mixed with the hydrocarbon while reaction takes place. In most cases the hydrofluoric acid charge should be at least 10 percent of the total charge, on a liquid volume basis, and hardly ever need exceed 50 or 60 percent, though more can, at times, be used. In the concentrated form, hydrofluoric acid is substantially inert, or non-corrosive, toward numerous metals, such as copper, nickel, most steels, and various other alloys which can be used in the construction of plant equipment. Occasional fortuitous reactions may produce minor amounts of inorganic fluorides but, as previously discussed, insofar as this invention is concerned hydrofluoric acid is considered to be used in the substantial absence of added metals or metal halides. The reaction temperature may be varied over a wide range for any particular reaction mixture, but appears to be most dependent upon the paraffin hydrocarbon participating in the reaction. Thus, in general, I may carry out an alkylation process at temperatures between about 0 and 300 or 400° F.

I have found that when an intimate mixture of a normal paraffin hydrocarbon, concentrated hydrofluoric acid, and an olefin hydrocarbon is maintained at a reaction temperature, a union takes place between the normal paraffin and the olefin to form a higher boiling paraffin which generally represents the sum of the original paraffin and olefin not only as to molecular weight but also as to molecular structure. Butanes are ordinarily too light to be included in most motor fuels in appreciable quantities, so that they will form the usual paraffinic reactants. While pentanes are present in most motor fuels in appreciable proportions, it will at times be desirable either to utilize excess pentanes or produce a fuel of very low volatility and pentanes, or heavier paraffins, may be used as reactants in such cases. Highly branched isoctanes can be produced either by alkylating butanes with butylenes or by alkylating pentanes with propylene, while highly

branched isononanes will result from the alkylation of pentanes with butylenes and will have low volatilities and vapor pressures. I have also found that higher temperatures are necessary for the alkylation of normal paraffins, and that they may be caused to react with olefins in the presence of concentrated hydrofluoric acid at elevated temperatures which heretofore could not be applied to mixtures of aliphatic hydrocarbons and concentrated mineral acids because of excessive deleterious side reactions. Thus, I conduct the reaction of normal paraffins with olefins at temperatures above about 120° F., preferably within the range of 150 to 300° F., but in some instances as high as 500 or 600° F. While the alkylation of normal paraffins may be carried out under only slight superatmospheric pressures, it is preferable to operate under substantial superatmospheric pressures, such as about 100 to 1,000 or 2,000 pounds per square inch or more. The process is preferably conducted with at least an appreciable portion of the reactant material in liquid phase, although this is not necessary for all reactants. When the process is conducted with a substantial portion of the reactants in liquid phase, the reaction temperature should not be above the critical temperature of the highest boiling reactant, and the pressure should be at least no less than the vapor pressure of this reactant, and preferably should be at least 500 pounds per square inch. Since the alkylation temperatures, even in the upper part of the range indicated, are still rather moderate, the pressures ordinarily need not be excessively above the vapor pressure of the reacting mixture and can, of course, be as low as can be shown by trial to permit effective alkylation. In many instances normal paraffins can be alkylated in the presence of hydrofluoric acid at pressures between 50 and 500 pounds per square inch. With some of the lower boiling and less reactive of the paraffins, it may be desirable to conduct the alkylation at a temperature in the upper part of the range indicated.

It appears that if a mixture of paraffins and olefins containing a large portion of olefins, such as 30 to 50 mol percent, or more, of the total mixture, is reacted in the presence of concentrated hydrofluoric acid, the molecular weight of the hydrocarbon product tends to be higher than would result if the same amount of olefin and paraffin were reacted by adding small amounts or portions of olefin to a predominantly paraffinic mixture in the presence of hydrofluoric acid, while allowing reaction to take place between and during the addition of olefins. While it seems that, in many instances with various particular olefin and paraffin reactants, some type of olefin-consumption reaction occurs very rapidly, so that immediately after olefin-containing material is introduced to the reaction zone the concentration of free olefin rapidly approaches a low value—often less than one percent—and is difficult to determine experimentally as to amount, more lower molecular weight products generally result, especially with the more reactive olefins, if high momentary concentrations of olefins in the reacting mixture are not obtained or permitted to result. Any olefin-consumption reaction which takes place under these conditions is exothermic, and for a close control of the reaction, heat should be removed as it develops. It is, of course, possible to produce a paraffinic product when the total charge stock contains more than 50 mol per-

cent olefins. When there is high initial concentration, such as first mentioned, it appears that in some cases a certain amount of polymerization first takes place, which of course reduces the mol percent of olefin, and a heavy product forms with these polymers as reactants. In other cases, the initial paraffinic product again is alkylated with additional olefin. The ultimate result is somewhat similar in both cases but not always the same.

It has, therefore, been found to be quite desirable to supply small amounts of olefins as these are consumed. When separate streams of paraffins and olefins are available, this can be accomplished in a continuous process by dispersing olefins in the reacting stream as reaction progresses, as by adding olefins at a plurality of points along the course of the reacting stream in a manner designed to effect rapid dispersal within the reacting medium. When the olefins and paraffins to be reacted are in the same mixture, with olefins in a rather high concentration, a suitable low concentration may be established and maintained by recirculating a portion of the effluent of the reaction zone back through this reaction zone, using it to dilute the incoming charge stock. When this latter modification is used, a portion, or portions, of the charge stock may be added at various points along the course of the reacting stream, thus reducing the amount of the recycle stream necessary to maintain an initial low concentration. In these modifications opportunity should, of course, be provided for abstraction of heat as reaction proceeds, and before further olefin addition. I have found that the most desirable results are obtained when the amount of olefin added to any particular part of the reacting mixture is not greater than about 10 mol percent of the total hydrocarbon material present, at the immediate zone of addition. Thus, in a continuous operation, wherein an olefin-containing stream is added at a point or zone of introduction to a paraffinic stream, this is to mean that the amount of olefin in this olefin-containing stream does not exceed the specified mol percent of this stream plus the reactant stream. A suitable time for reaction, and abstraction of heat, should be allowed before again adding olefin, and generally 50 to 75 percent or more of the olefin previously added should be allowed to react before additional olefin is added. When reacting some paraffin and olefin mixtures, especially those containing less reactive olefins, olefin consumption reactions are not so rapid and somewhat higher olefin concentrations may be maintained in the reacting stream without resulting in too great an increase in the proportion of products of higher molecular weights. When the charge stock is especially reactive the added olefins may need to be kept as low as 1 or 2 percent for any particular point or zone of olefin introduction, but generally satisfactory conditions will be found when the added olefins are between 2 and 8 percent of the total stream. When an easily polymerizable olefin, such as isobutylene, is one of the principal olefin reactants, or when the process is carried out at elevated temperatures with somewhat less reactive paraffins, such as temperatures between about 125 and 300° F., it will generally be desirable to add only small amounts of olefins at any one point, with a substantial amount of recycle and/or many points of olefin addition.

Olefins over a wide range of molecular weights

and structures are suitable to use in the alkylation of paraffins in the presence of concentrated hydrofluoric acid. One of the principal commercial applications of my invention at present is the production of paraffin hydrocarbons in the motor fuel range from lower boiling hydrocarbons, and for this reason olefins of five or fewer carbon atoms per molecule are more often preferred. Of these, ethylene enters into reaction least readily, especially in the absence of olefins of more carbon atoms per molecule. While pentenes are generally considered to be in the motor fuel boiling range, it will often be desirable to decrease the amount of C₅ hydrocarbons in a final product for reasons of volatility, or a high boiling fuel of low vapor pressure may be desired, so that it will not be unusual to use pentenes. Hexenes, heptenes, octenes, and the like are more often of greater value as they are, although they are not to be excluded in the broadest concepts of this invention. Cycloolefins, such as cyclopentene, cyclohexene, and the like, also enter into reaction as ordinary aliphatic olefins.

The reaction period, during which olefin is introduced, reacted and consumed to produce eventually a paraffinic product, is dependent to a certain extent upon the reaction temperature and the total amount of olefins reacted. A period between 15 minutes and 2 hours has been found satisfactory in most cases, but at higher temperatures a reaction period as low as about 5 minutes, or somewhat less, will often be sufficient. At lower temperatures and low olefin concentration, which is preferred at times when preparing certain especially pure products, periods as high as 4 or 5 hours may be found most desirable.

It will be understood, of course, that all these reaction variables are more or less interdependent, and that when one is arbitrarily fixed the limits within which others may be varied are somewhat restricted. The more desirable ranges for ordinary applications of my invention have been indicated, and can also be ascertained from the specific examples presented hereinafter. However, for any particular application of my invention, the most desirable conditions can be readily determined by trial by one skilled in the art, such a determination being facilitated by the discussion of trends of these variables presented herewith.

As previously mentioned, when the modification of my invention is practiced which includes a preliminary selective alkylation of isoparaffins any one of a number of catalysts may be used, although not under completely equivalent conditions nor with completely equivalent results. Some of these catalysts, such as concentrated sulfuric acid, appear to be adapted to effect the alkylation only of the isoparaffins in a paraffin mixture. When more active catalysts are used, the temperature and reaction times can be so correlated, and adjusted by trial for specific instances, that substantially no normal paraffins enter into the alkylation conditions. In some instances, as with aluminum chloride, the reaction temperature for this selective alkylation step may be well below ordinary atmospheric temperatures. In any case, the isoparaffins in the initial charge stock are generally not completely reacted, but are substantially the only paraffinic reactant and are markedly reduced in concentration, at least to less than 10 percent of the total unreacted paraffin hydrocarbon material. Isoparaffins should be present in the initial charge stock in substantial amounts, preferably

more than 25 percent and generally not less than about 15 percent. Adequate concentration steps, such as fractional distillation, may be used to obtain a satisfactory composition for the charge stock.

After the selective alkylation of isoparaffins, the heavier hydrocarbon material, or alkylate, so produced is readily separated by fractional condensation or distillation, and unreacted paraffins are subjected to alkylation in the presence of hydrofluoric acid. When catalysts other than hydrofluoric acid are used in this first step, they should also be separated from the effluent, by suitable means adapted to the catalysts used. I prefer to use concentrated hydrofluoric acid in this first step, in which case the total effluent of this first alkylation step may be subjected to a single fractional distillation to separate, as a kettle product, the heavier hydrocarbons, and as a lighter overhead product a mixture of unreacted hydrocarbons and hydrofluoric acid, which, if desired, can be passed directly to the second alkylation step.

Reference will now be made to the accompanying drawing which forms a part of this specification, and which illustrates diagrammatically by means of a flow sheet one arrangement of apparatus suitable for practicing my invention. It will be described as a specific embodiment for the production of paraffinic hydrocarbons in the boiling range of motor fuel from butanes and/or pentanes, and also serves as one example of my invention. However, it will be understood that other charge stocks may be used and products of other boiling ranges produced, with suitable modifications for any particular case as will be readily ascertained, as just discussed.

A paraffinic hydrocarbon fraction, such as a butane fraction from natural gas containing about 30 percent isobutane, enters the system under a suitable pressure such as 20 to 200 pounds per square inch gauge, thru pipe 10 and valve 11, and is passed to a reaction zone 12 in alkylator 13, such as the tube coil diagrammatically shown which is satisfactory for use with a fluid or mobile alkylation catalyst. Such a catalyst, as sulfuric acid, hydrofluoric acid, or the like, is passed through pipe 14 and valve 15, and can be thoroughly mixed with the paraffinic stream passing through pipe 10. Olefin hydrocarbons enter the system thru pipe and manifold 16 and valve 17, and may be accompanied by a certain amount of paraffinic material similar to that passing thru pipe 10, such as butane. Active churning action with fluid or mobile solid catalysts may be obtained by stirring means in an enlarged reaction zone, or by baffles, orifices, and the like, in a tube coil of restricted cross section, whereby the alkylating catalyst and hydrocarbons are intimately intermixed, and churned, as shown in this particular modification, preferably to a sufficient extent to effect emulsification. When a solid granular catalyst is used, such as sodium chloroaluminate deposited on a solid granular support, it may be used in an elongated catalyst chamber, or in a series of small chambers, as may be desired.

The olefins are added to the paraffin stream at one or more points, as may be desirable, through pipes 20, 21, 22, and 23, controlled by valves 25, 26, 27, and 28, respectively, which lead to various points in the reaction zone. These olefins may be produced by dehydrogenation, cracking, depolymerization, or polymerization, or the like, and are ordinarily somewhat diluted

with saturated material. Thus, when butenes are reacted with butanes to produce octanes, the butenes may previously be produced by dehydrogenation of butane, and may be accompanied by unreacted butane. At other times, when the olefins are originally in more concentrated form, such as when polymers are used or an olefin concentrate is formed by depolymerization, paraffin hydrocarbons such as butane may be deliberately added, if desired. It will be noted that pipe 20 introduces olefins into the paraffin stream immediately before it enters the reaction zone 12, and at times this may be the only point of addition. Also, when a hydrocarbon material containing a relatively low amount of olefins is available, such as less than about 15 or 20 percent, this material can be added thru pipes 10 or 16 as the sole charge to this part of the process. Such a modification is preferably used in connection with a recirculation of a part or portion of the effluent of the reaction zone passing thru pipe 30. Such a recirculation is accomplished by passing a portion of the effluent from pipe 30 thru pipe 33, valve 34, pump 35 and pipe 36 controlled by valve 37 back to pipe 10 at the inlet of the reaction zone. In any method of olefin addition it is well to keep the amount of olefin added low at any one point of olefin addition, such as below 10 mol percent of the total hydrocarbons present, and the olefin concentration maintained may sometimes be very low, below 1 percent, as previously discussed. However, by the practice of my process a large amount of reaction can be secured by continuously adding olefin to the reacting stream as previously added olefin is consumed, as by a plurality of points of addition represented by pipes 20 to 23, inclusive. With such controlled addition of olefins, the reaction time may be somewhat extended to produce a substantial total yield.

The reaction effluent is passed thru pipe 30 and valve 31 to separating means 40, wherein a separation is made between the product of the reaction with isobutane, or alkylate, and lower boiling material comprising unreacted paraffins. The alkylate is withdrawn thru pipe 41 and valve 42, and may be subjected to such other treatment, such as fractionation, caustic washing, and the like, as may be desired or necessary. Traces of acid, acidic materials, and the like may be removed by suitable treatment, as by contacting with hot or cold alkali. When a fluid or mobile solid catalyst accompanies the effluent into separating means 40, it may be removed by suitable means such as filtration, fractionation, centrifuging or the like, dependent upon the characteristics of the catalyst. A low boiling catalyst may be removed by fractionation thru pipe 43 and valve 44. Unreacted, low boiling paraffins may then be separated thru pipe 47, and are preferably passed to the second step of the process thru pipe 45 and valve 49 to pipe 50, or may be discharged, at least in part, thru valve 48.

It is to be understood that the representation of separating means 40 is diagrammatic, and will in practice comprise various pieces of fractionating and separating equipment, according to the effluent material to be treated. When solid, stationary alkylation catalysts are used in the reaction zone 12, the effluent material will be principally a hydrocarbon mixture easily separated by fractional distillation. When a solid mobile catalyst, such as certain finely divided

5 metal chlorides, is used filtration or similar separating steps may be included. Sulfuric acid may be readily separated from hydrocarbons by settling or centrifuging, and the hydrocarbons subsequently separated by fractionation.

10 In a preferred form, concentrated hydrofluoric acid is used in the first step, and the separating means 40 may consist of simple fractional distillation equipment, with the alkylate withdrawn as a kettle product and the unreacted paraffins and hydrofluoric acid withdrawn as an overhead product thru pipe 43. This overhead product may then be passed thru pipe 50 and valve 46 to the second alkylation step, to be described.

15 A paraffin hydrocarbon material, comprising essentially normal paraffin such as normal butane, is passed thru pipe 50 to a reaction zone 52 in alkylator 53, such as the tube coil diagrammatically shown. It may consist of unreacted paraffins from the preceding step, as just described, or when this is not a part of the process, the paraffins are added from any suitable source thru pipe 78 and valve 79, passing thru pipes 83 and 76 to pipe 50. Concentrated hydrofluoric acid, preferably between 80 and 100 percent hydrofluoric acid, is added as needed thru pipe 54 and valve 55, to be thoroughly mixed with the paraffinic stream passing thru pipe 50. The total amount of hydrofluoric acid present in the reaction zone 52 should be such that, when the subsequent reaction takes place in liquid phase as will most often be the case, the liquid hydrocarbon material is substantially saturated with hydrogen fluoride, and preferably about 10 percent or more of the total mixture is hydrofluoric acid. Olefin hydrocarbons enter the system thru pipe and manifold 56 and valve 57, and may be accompanied by a certain amount of paraffinic material similar to that entering thru pipe 50, such as butane. Active churning action may be obtained by stirring means in an enlarged reaction zone, or by baffles, orifices, and the like, in a tube coil of restricted cross section, whereby hydrofluoric acid and hydrocarbons are intimately intermixed, and churned, as is shown in this particular modification.

20 The alkylation of normal paraffins in reaction zone 52 may be carried out in a much similar manner to that just described in connection with the reaction zone 12, especially when hydrofluoric acid is used as the alkylation catalyst in zone 12. Thus olefins may be added to the reacting stream at one or more points, as may be desirable, through pipes 60, 61, 62, and 63, controlled by valves 65, 66, 67, and 68, respectively, which lead to various points in the reaction zone. These olefins may be produced by dehydrogenation, or the like, as previously set forth. Thus, when butenes are reacted with butanes to produce octanes, the butenes may previously be produced by dehydrogenation of butane, and may be accompanied by unreacted butane. At other times, when the olefins are originally in more concentrated form, such as when polymers are used or an olefin concentrate is formed by depolymerization, paraffin hydrocarbons such as butane may be deliberately added, if desired. It will be noted that pipe 60 introduces olefins into the paraffin stream immediately before it enters the reaction zone 52, and at times this may be the only point of addition. Also, when a hydrocarbon material containing a relatively low amount of olefins is available, such as less than about 15 or 20 percent, this material can be added thru pipes 50

or 56 as the sole charge to the process. Such a modification is preferably used in connection with a recirculation of a part or portion of the effluent of the reaction zone passing thru pipe 70. Such a recirculation is accomplished by passing a portion of the effluent from pipe 70 thru pipe 73, valve 74, pump 75 and pipe 76 controlled by valve 77 back to pipe 50 at the inlet of the reaction zone. In any method of olefin addition it is well to keep the amount of olefin added low at any one point of olefin addition, such as below 10 mol percent of the total hydrocarbons present, and the olefin concentration maintained may sometimes be very low, below 1 percent, as previously discussed. However, by the practice of my process a large amount of reaction can be secured by continuously adding olefin to the reacting stream as previously added olefin is consumed, as by a plurality of points of addition represented by pipes 60 to 63, inclusive. With such controlled addition of olefins, the reaction time may be somewhat extended to produce a substantial total yield.

At reaction temperatures of about 150 to 300° F., which ordinarily are suitable for the alkylation of normal paraffins such as normal butane and normal pentane, the reaction time should preferably not be less than about 5 minutes, and with very small amounts of olefin addition, and reaction temperature in the lower part of the range indicated, they may be as much as 3 hours or more. Generally, a satisfactory time will be found between 15 minutes and 2 hours for such materials.

The reaction effluent, comprising primarily paraffins and hydrofluoric acid, passes thru pipe 70 and valve 71 to fractionating means 80, wherein a separation is made between the product, or alkylate, and lower boiling material, comprising predominantly unreacted paraffins and hydrofluoric acid. The alkylate is withdrawn thru pipe 81 and valve 82, and may be subjected to such other treatment, such as fractionation, caustic washing, and the like, as may be desired or necessary. Traces of the acid and of alkyl fluorides may be removed by suitable treatment, as by contacting with hot or cold alkali. The fractionating means 80 is diagrammatically represented as a single fractionating column, which is to be supplied with suitable bubble trays or the like, heating means for the bottom and cooling means for the top, as is well known in the art, but which are not shown. However, if necessary or desirable, the fractionating means may comprise two or more fractionators and their auxiliary equipment, as will be readily understood. Lower boiling material is removed thru pipe 83, and may be returned entirely or in part directly to the reaction zone thru valve 84 for further reaction.

More often, however, it will be desirable to subject at least a part of this material to further treatment, and in such an event all or part of the stream is passed from pipe 83 thru pipe 85, cooler and condenser 86, pipe 87 and valve 88 to separator 90. The pressure prevailing in the system at this point is appreciably above atmospheric, a pressure of the order of 30 to 150 pounds per square inch gauge is effective, and the cooler and condenser 86 is operated so as to reduce to liquid condition both hydrocarbon and hydrofluoric acid and permit a separation of liquid hydrocarbons from the denser liquid hydrofluoric acid to take place. Generally, ordinary

cooling water will provide sufficient cooling, and if the pressure is not sufficient at this temperature to result in a condensation, it may be boosted by a compressor, not shown, in pipe 85. Hydrofluoric acid is withdrawn through pipe 91, and may be discharged thru valve 92. Any portion of this material may be returned to the reaction thru pipe 93, and valve 94, passing to pipe 54, and generally a substantial portion is so recycled.

A hydrocarbon fraction, still containing a minor amount of dissolved hydrofluoric acid, but comprising principally unreacted butane is removed from separator 90 thru pipe 95, and may be discharged thru valve 96. However, it will generally be desirable to subject this material to further treatment, and any part or all of it is then passed from pipe 95 thru pipe 97 and valve 98 to fractionating means 100. Again, this may be a simple fractionating column, with suitable bubble trays, heating means, and cooling means, not shown, or may be a combination of two or more fractionators and/or separators. A paraffin hydrocarbon material, such as butane, is recovered in a substantially pure state as a kettle product, which is removed thru pipe 101, and may be recovered for further use or treatment thru valve 102. In most cases it will be desirable to recycle directly at least a substantial portion of this material, and such a portion is passed from pipe 101 thru pipe 103 and valve 104, to pipe 50 and on to the reaction zone. With the previous removal of the major part of the hydrofluoric acid as a liquid thru pipe 91, only minor amounts will remain in the hydrocarbon stream passing thru pipe 95. In such low concentrations in the charge to fractionating means 100, it can be made to pass overhead thru pipe 105, even in the presence of some lower boiling hydrocarbons, as a part of an azeotropic mixture, leaving substantially pure hydrocarbons in the kettle to be withdrawn thru 101 as discussed. The vapor fraction, which contains appreciable quantities of hydrofluoric acid, is removed thru pipe 105, cooler and condenser 106, pipe 107 and valve 108 to separator 110. The cooling in 106 is sufficient to cause a condensation of hydrofluoric acid and a separation of a major part of it from the hydrocarbon material as a separate heavy liquid phase, which is withdrawn thru pipe 115, and may be either returned to the system thru pipe 117 and valve 118, and pipe 54, or removed in part, or entirely, thru valve 116. The light hydrocarbon material, which will contain only a small amount of hydrofluoric acid, is removed from separator 110 thru pipe 120, and is preferably returned to fractionating means 100 thru pipes 111 and 97, and valve 112. If desired, a part may be recirculated thru valve 123.

With this preferred arrangement, a state of equilibrium can be reached whereby even relatively light hydrocarbons can be recovered from the kettle product of fractionating means 100, and removed thru valve 102, with substantially all of the hydrofluoric acid being recycled thru pipes 93 and 117, and such a mode of operation forms a modification of this invention. However, if desired a part, or all, of the material passing thru pipe 120 may be removed from the system thru valve 121. If the hydrofluoric acid content renders this material difficult to handle or undesirable to let free, it may be treated in scrubber 126 by being passed thru pipe 124 and valve 125. Water, or an alkali solution such as sodium hydroxide, or the like, is introduced thru pipe 127

and valve 128, and is used to wash the hydrocarbon stream entering thru pipe 124. Purified hydrocarbons are removed thru pipe 130 and valve 131, while the wash liquid is removed thru pipe 132 and valve 133. If desired, a part or all of the stream passing thru pipes 95 and 97 may be sent to scrubber 126 thru pipe 113 and valve 114.

It will be understood that the flow diagram presented and described herewith is schematic only, and that many additional pieces of equipment, such as pressure gauges, valves, flow meters, pumps, heat exchangers, controllers, reflux accumulators, reflux lines, and the like, will be necessary for any particular installation, and can be installed by anyone skilled in the art. However, the essential equipment and material flow have been described in sufficient detail to serve as an efficient guide. Alkyl fluorides, which may be found in minor amounts, generally will accompany the alkylate product. They may be separated therefrom by any desirable means, as by caustic alkali treatment, solvent extraction using an alcohol, or other suitable means. While it will generally be more desirable to conduct my invention in a continuous manner, some part or all of it may, of course, be conducted by batches.

Example I

As an example of the practice of my invention, a mixture of substantially anhydrous hydrofluoric acid and normal butane was charged to a reaction chamber which was maintained at a temperature between 215 and 225° F., and under a pressure between 400 and 500 pounds per square inch. The initial ratio of the volume of liquid normal butane and liquid hydrofluoric acid was about 2:1. To this mixture in the reaction zone was added a mixture of normal butane and propylene over a period of about 80 minutes while the entire mixture in the reaction zone was continuously agitated to effect an intimate mixing and emulsification of the liquid hydrofluoric acid with the liquid hydrocarbon reactants. In order to insure reaction, the reactants were maintained under the reaction conditions for an additional period of about 4 hours, although it later appeared that such an extended reaction period was not necessary. The mol ratio of total normal butane to total propylene added was about 2.7:1. The reaction products were cooled, the major part of the hydrofluoric acid was separated as a heavy liquid, unreacted light hydrocarbons were separated by vaporization, and the liquid hydrocarbon product was subjected to analysis with the following results.

Boiling range, ° F.	Ap- prox- imate for- mula	Density at 77° F.	Refrac- tive index at 68° F.	Vol- per cent of total prod- uct	Per cent un- sat.
80-140	C_4H_{12} and C_6H_{14}	0.6660	1.3802	7.7	0.0
140-208	C_7H_{16}			19.5	
208-260	C_8H_{18}	0.6960	1.3961	19.2	0.0
260-302	C_9H_{20}	0.7167	1.4056	13.3	0.6
302-350	$C_{10}H_{22}$	0.7320	1.4136	11.1	1.5
350-410	$C_{11}H_{24}$ and $C_{12}H_{26}$	0.7523	1.4220	12.3	2.1
410	$C_{13}H_{28}$	0.8023	1.4480	16.9	
Total product		0.7138	1.4049	100.0	1.8

Although the extended reaction period induced somewhat extensive secondary reactions, the pre-

dominant fraction consist of heptanes formed by the reaction

and over 80 percent of the reaction product was in the present day gasoline boiling range, was over 98 percent saturated, and had a well balanced distillation range.

Example II

As an example of the operation of a modification of my process using two different catalysts, a butane fraction from a natural gasoline plant, containing about 35 percent by volume of isobutane, may be reacted with a butane-butylene fraction, produced by dehydrogenation over black unglowed chromium oxide deposited on bauxite, or a similar butane fraction. The first alkylation reaction is carried out in the presence of an equal volume of 98 percent sulfuric acid at a temperature of about 85° F. and a pressure of 50 pounds per square inch gauge with vigorous agitation to produce a saturated product of which over 80 percent boils below 400° F. From the effluent of the reaction zone is separated the sulfuric acid, a part of which is returned for further reaction. The hydrocarbon fraction of the effluent is separated by simple fractionation into a pentane and heavier fraction, which consists principally of iso-octanes and which is removed for further treatment. The butane and lighter fraction, which contains only about 7 percent isobutane with the rest being predominantly normal butane, is admixed with an equal volume of hydrofluoric acid of a concentration greater than 95 percent. The mixture is passed thru a long tube coil of restricted cross-sectional area at a high velocity to insure intimate mixing and emulsification of liquid hydrofluoric acid with the liquid hydrocarbon reactants, and olefins, predominantly butanes, are added along the length of the coil, at about 12 points. The temperature is maintained at about 275° F., and the coil is of such a length that the total reaction time is about 25 minutes. The effluent is cooled to about 80° F., the hydrofluoric acid separated by settling and returned to the inlet end of the tube coil, and the hydrocarbon fraction is passed thru a sodium hydroxide washer to a fractionating column. The unreacted butane fraction is separated and is suitable for catalytic dehydrogenation to produce olefins for further alkylation. The product boiling in the motor fuel range is over 96 percent saturated, and has a predominant portion of octanes along with appreciable portions of lower boiling paraffins which have been formed by secondary reactions and which give the product a balanced distillation range.

Many modifications and variations of this invention may obviously be used, and can be adapted by one skilled in the art without departing from the spirit of the disclosure. The restrictions used in the examples, and in connection with the drawing, need not necessarily be used as limits for any particular operation or set of conditions, as they are presented primarily as illustrative examples.

I claim:

1. A process for synthesizing hydrocarbons, which comprises reacting in liquid phase at a temperature of at least 120° F. a low boiling normal paraffin liquefiable at said temperature and an olefin in the presence of an alkylating catalyst consisting essentially of liquid concentrated

hydrofluoric acid under superatmospheric pressure and suitable alkylating conditions of temperature and time.

2. A process for producing a paraffinic material from lighter normal paraffin and olefin hydrocarbons, which comprises simultaneously contacting such a normal paraffin hydrocarbon and an olefin hydrocarbon with concentrated hydrofluoric acid as the sole alkylation catalyst at a controlled reaction temperature, and correlating the amount of hydrofluoric acid, the reaction temperature, pressure, and time, and the proportion of olefin to paraffin to effect alkylation of the normal paraffin as the principal reaction of the process, with minimum olefin polymerization, to produce a heavier paraffinic hydrocarbon material.

3. A process for the production of higher boiling paraffin hydrocarbons from lower boiling paraffin hydrocarbons, which comprises adding to a stream of predominantly low boiling normal paraffins heavier than ethane, maintained at a suitable temperature and pressure to effect alkylation of said low-boiling normal paraffins, in the presence of concentrated hydrofluoric acid, successive small quantities of a monoolefin in such amounts that the amount of olefin added to the mixture at no time exceeds the equivalent of 10 mol percent of the total hydrocarbons present.

4. A process for synthesizing hydrocarbons, which comprises reacting under a superatmospheric pressure and in liquid phase at an alkylation temperature of at least 120° F. a low boiling normal paraffin liquefiable at said alkylation temperature and an olefin in the presence of liquid concentrated hydrofluoric acid as the sole alkylation catalyst, and dispersing said olefin in the reaction mixture during said reaction in such a manner that the content of olefins added to the mixture at no time exceeds the equivalent of 10 mol percent of the total hydrocarbons present.

5. A process for synthesizing hydrocarbons which comprises reacting normal butane with an olefin under alkylation conditions and in the presence of an alkylation catalyst consisting essentially of concentrated hydrofluoric acid.

6. A process for synthesizing hydrocarbons which comprises reacting normal pentane with an olefin under alkylation conditions and in the presence of an alkylation catalyst consisting essentially of concentrated hydrofluoric acid.

7. A process for the production of higher boil-

ing paraffin hydrocarbons from lower boiling paraffin hydrocarbons, which comprises adding to a stream consisting predominantly of low boiling normal paraffins heavier than ethane maintained at a suitable alkylation temperature in excess of about 120° F. and not greater than 500° F. under a superatmospheric pressure and in the presence of concentrated hydrofluoric acid as the sole alkylation catalyst successive small quantities of at least one olefin of not more than five carbon atoms per molecule in such amounts that the content of olefins added to the mixture at no time exceeds the equivalent of 10 mol percent of the total hydrocarbons present.

8. A process for synthesizing hydrocarbons, which comprises reacting a normal paraffin heavier than ethane with an olefin under alkylation conditions and in the presence of an alkylation catalyst consisting essentially of concentrated aqueous hydrofluoric acid to produce a paraffin hydrocarbon of higher molecular weight.

9. A process for synthesizing hydrocarbons from lower boiling paraffin hydrocarbons, under a superatmospheric pressure and in liquid phase at an alkylation temperature of at least 120° F. which comprises reacting a low boiling normal paraffin liquefiable at said alkylation temperature and an olefin in the presence of liquid concentrated aqueous hydrofluoric acid as the sole alkylation catalyst.

10. A process for the synthesis of normally liquid hydrocarbons from normally gaseous hydrocarbons, which comprises adding to a stream containing predominantly normal butane maintained at a superatmospheric pressure of about 400 to 500 pounds per square inch and at an alkylation temperature between 150 and 300° F. and in the presence of concentrated hydrofluoric acid in an amount between 10 and 50% by weight of the reactants successive small quantities of propylene in such amounts that the content of olefin in the mixture at no time exceeds the equivalent of 10 mol per cent of the total hydrocarbons present.

11. A process which comprises contacting a low-boiling normal paraffin hydrocarbon heavier than methane with an olefin hydrocarbon in the presence of concentrated hydrofluoric acid as the sole catalytic alkylation component and under conditions to effect alkylation of said normal paraffin hydrocarbon with said olefin hydrocarbon to produce a higher boiling paraffin hydrocarbon.

FREDERICK E. FREY.
